UNITED STATES PATENT OFFICE

144,566

DESIGN FOR A TOY TELEPHONE

Frank M. Hoover, Youngstown, Ohio, and Austin Homer, Merion, Pa., assignors to H. M. C. Company, Youngstown, Ohio, a copartnership

Application August 10, 1945, Serial No. 121,354

Term of patent 14 years

(Cl. D34—16)

To all whom it may concern:

Be it known that we, Frank M. Hoover and Austin Homer, both citizens of the United States, residing respectively in Youngstown, in the county of Mahoning and State of Ohio, and Merion, in the county of Montgomery and State of Pennsylvania, have invented a new, original, and ornamental Design for a Toy Telephone, of which the following is a specification, reference being had to the accompanying drawing, forming part thereof.

In the drawing:

We claim:

The ornamental design for toy telephone, substantially as shown.

FRANK M. HOOVER.
AUSTIN HOMER.
